UNITED STATES PATENT OFFICE.

WILLIAM S. WELLS, OF BETHLEHEM, PENNSYLVANIA, ASSIGNOR TO BENJAMIN EAST WOOD COMPANY, OF PATERSON, NEW JERSEY, A CORPORATION OF NEW JERSEY.

SHUTTLE BOX.

Application filed October 10, 1924. Serial No. 742,768.

In the ordinary box loom there is a strap connecting the picker stick and loom frame and which, as the batten moves rearward, acts to draw the stick inward somewhat so that the picker (thus moved inward by the stick) stops the shuttle short of the outward limit of movement of the picker; and when the batten now moves forward and the strap relaxes the usual spring acting on the picker stick shifts it and consequently the picker back to their original or fully outward positions. The object of this is to clear the shuttle and picker from each other preparatory to the shifting of the boxes, especially as the point of the shuttle usually wears a recess in the picker and the box shifting could not be effected with the point of the shuttle engaged in this recess. The time required to thus clear the picker from the shuttle after the latter is checked reduces the time available for the shifting of the boxes, and one object of this invention is to provide for the stopping of the shuttle without moving the picking means inward to receive its impact and hence having to be reset in order to clear the shuttle for the changing of the boxes. This I accomplish by constructing the box and shuttle so that the flight of the shuttle is stopped short of actual contact of the shuttle with the picker, then in its fully outward or retracted position, in the best form forming the shuttle and box so that one of them at least presents to the other an oblique shoulder used in accomplishing the stopping of the shuttle. In my shuttle box, the shuttle after undergoing gradual retardation in entering the box is finally brought to a positive stop at a definite point in the box. And in this connection I may remark that ordinarily in shuttle boxes a so-called swell, presenting appreciable curvature at its inner or shuttle-contact face and usually inflexible, forms one wall of the box. Consequently, when the shuttle enters the box, although the swell is yieldingly backed by a spring, its nose is deflected toward the opposite wall producing a series of rebounds of the shuttle back and forth from one to the other of said wall and swell, the whole action representing a considerable shock and sudden stopping of the shuttle (with incidental noise) which wears the shuttle and box and loosens and breaks down the weft package; and when the shuttle leaves the box the swell,

due to its appreciable convexity, tends by pressure on the tapering rear end of the shuttle, to veer or cant it out of its true course. In the shuttle-box herein set forth these objections are overcome, the shuttle entering the box and coming to a stop smoothly and gradually, without jar and practically noiselessly, and both entering and leaving the box entirely free of any influence tending either to deflect it or veer or cant it from its true position and path of movement across the batten. This is due to forming the opposite surfaces of the box straight and so that they are in permanent substantially parallel relation to each other, notwithstanding one such wall is flexible and is elastically pressed toward the other, and to providing the box at both sides of the path of the entering shuttle with stops arranged to be simultaneously engaged by, and thus adapted to check, the shuttle.

In the drawing, Fig. 1 is a front elevation of the box portion of the batten structure of a box loom, with a shuttle therein, and of the picker stick and picker.

Fig. 2 is a plan, partly in section, of what appears in Fig. 1; and

Fig. 3 is a plan of the shuttle.

In the drawing, A is a batten and B is the shuttle.

The batten A has as usual a slot (not shown) to receive the picker stick 1 which engages in a suitable hole in the picker 2. The picker is arranged in a housing 3 on a plate 4 secured on the batten A and when the picker is shifted inwardly by the picker stick it moves off the plate 4 onto a plate 5 which forms the bottom wall of the shuttle-box structure. This shuttle-box structure 6 is suitably guided to move horizontally and transversely of the batten on the plate 4 by any suitable means. Up-standing from the plate 5 of the structure 6 is a longitudinal central partition 7 which divides the box structure into two cells or shuttle-boxes; at each side of the partition 7 the wall 5 has a slot 8 to register with the slot of the batten in which the picker stick moves and which receives the picker stick during its movements.

The inner and bottom walls of each cell being formed by the partition 7 and wall 5, respectively, the top wall thereof is formed by a flange 9 at the top of partition 7; this

coactive with the latter to grip the shuttle, and the box having at said other end thereof and at both sides of said path stops arranged to be simultaneously engaged by, and thus 5 adapted to check such entering movement of, the shuttle.

2. A shuttle box including, in combination with a body structure having a straight shuttle-wiped surface extending lengthwise 10 of the shuttle path, an elastic strip arranged opposite and spaced from said surface and having the major part of its length between its ends forming another shuttle-

wiped surface and being straight and parallel with the first surface and its said ends 15 bent away from the same and both permanently held and supported against said structure, the box having at that end thereof toward which the shuttle moves on entering and while completing its entering move- 20 ment and at both sides of said path, stops arranged to be simultaneously engaged by, and thus adapted to check such entering movement of, the shuttle.

In testimony whereof I affix my signature.
WILLIAM S. WELLS.
